UNITED STATES PATENT OFFICE.

JOHN DEMAREST, OF NEW YORK, N. Y., ASSIGNOR TO THE J. L. MOTT
IRON WORKS, OF SAME PLACE.

WATER-CLOSET VALVE.

SPECIFICATION forming part of Letters Patent No. 292,159, dated January 22, 1884.

Application filed March 21, 1883. (No mod. 1.)

To all whom it may concern:

Be it known that I, JOHN DEMAREST, of the city and State of New York, have invented an Improvement in Valves for Water-Closets, of which the following is a specification.

In Letters Patent No. 260,953, granted to me, there is a stand-pipe with a valve at the lower end of a tubular dam within said stand-pipe.

My present invention relates to a valve that is specially adapted to water-closets provided with stand-pipes. In my improved valve a packing-gland is dispensed with; hence there is no risk of the stem being held by friction, and the action of the valve is more reliable. The thin sheet or jet of water that rushes through the hole around the valve-stem is received into a deflecting-thimble, and conveyed by a tube or hollow arm into the stand-pipe.

The valve is below the seat and closes upwardly, so that in the normal position there is no leakage of water, and the small quantity of water that escapes around the valve-stem is only running while the water flows from the valve into the basin of the closet.

In the drawings, Figure 1 is a vertical section of the valve and a portion of the stand-pipe, and Fig. 2 is a sectional plan at the line *xx*.

The stand-pipe *e*, cover *o*, cylindrical dam *k'*, the valve-stem *l*, pull *m*, and the pull-cup *n* are similar to those in my Patent No. 260,953, and do not require any further description. I remark that this stand-pipe may be of any suitable character, and it is only introduced herein for the purpose of illustrating the manner in which my improved valve may be applied to the stand-pipe of closets of the general character represented in said patent.

The water-supply pipe *u* is coupled to one side of the valve-case *b*, and in this valve-case *b* there is a valve, *a*, and valve-seat *c*, and above the seat there is a hollow arm, *e'*, with a coupling-screw at the end, by means of which a pipe is connected that passes to the basin of the water-closet, so as to supply the flushing-water to the said closet. The septum *i* is above this arm *e'*, and through it the stem *k* of the valve *a* passes, and above this septum *i*

there is a third hollow arm or tube, *g*, that is 50 of a sufficient length to be screwed into a hole in the side of the stand-pipe *e*. This hollow arm *g* is strong enough to support the valve-case and the valve-actuating lever, and it serves to convey into the stand-pipe any wa- 55 ter that may pass through the hole in the septum and around the valve-stem *k*. Upon the upper end of the valve-stem there is a deflecting-thimble, *m'*, that is hollowed out conically at its under side, so that any water that may 60 spurt up through the opening for the valve-stem will enter this thimble and be thrown down again into the tube *g* and run off to the stand-pipe. The exterior of the deflecting-thimble is cylindrical, and it slides freely in 65 the cylindrical upper portion of the valve-case at the end of the pipe *g*. In order to press upon this thimble and open the valve, I make use of the lever *r*, which has a fulcrum-pin, *s*, that passes through two lugs, *q*, upon the pipe 70 *g*—one at each side of the lever. In these lugs and lever there are two or more sets of holes for the fulcrum-pin *s*, so that said pin *s* may be changed in its position into either set of holes. When said pin is near the thimble, the move- 75 ment of the thimble with a given length of motion at the long end of the lever will be less than it will when the pin *s* is in the set of holes farthest from the thimble. By this means the valve will be opened more or less, 80 and, as said valve closes automatically, and by the action of a variable chamber, the time consumed in closing will vary, and a greater or less quantity of water will flow by the pipe *e'* to the water-closet basin.

I have represented the nut or shoulder *3*, upon the stem of the pull *l*, as the means for moving the lever *r*. In this instance the valve is opened at the same time that the dam *k'* is raised, so that the water will flow to the closet- 90 basin.

Upon reference to Fig. 1 it will be seen that the valve-case is made in two parts, screwed together, the lower part forming the variable chamber, in which the cup-leather piston *t* 95 slides. The valve-stem *k* is loose in the tubular stem *t'*, that connects the valve *a* and cup-leather piston. There are channels in or flat-

tened sides to the valve-stem, so that water will pass freely up around the spindle when the spindle is pressed down in opening the valve; but there is a valve, v , at the lower part 5 of the spindle, that closes against the bottom end of the tubular stem by the action of the spring v' when pressure on the upper end of the stem k is relieved, so that the variable chamber can only fill with water through the 10 small hole 6 as the cup-leather piston and the valve rise gradually.

In order to prevent the small hole at 6 becoming obstructed with sediment which accumulates around the cup-leather piston, I make 15 a tubular projection at one side of the stem k , and this rises above the cup-leather piston t , so that the small hole is above and out of the way of any sediment. Hence the valve is not liable to get out of order; but it will close with 20 regularity, and the water will run the desired time into the closet-basin according to the extent of movement given to the valve in opening it.

The valve may be taken out for cleaning by 25 simply unscrewing the bottom part of the valve-case without disturbing any of the parts that connect to the water-pipes.

I claim as my invention—

1. The valve-case and the valve having a 30 stem passing through a septum in the case, a

tubular arm, g , above the septum, extending to the closet, and a deflecting-thimble upon the upper end of the valve-stem, substantially as set forth.

2. In a water-closet valve, the combination, 35 with the valve-case, of the arm g , the lever above said arm for actuating the valve, flanges, and holes in the flanges and lever, and a movable pin by which the position of the fulcrum and the movement of the valve may be varied, 40 substantially as set forth.

3. In combination, with the stand-pipe in a water-closet and the pull thereof, a valve and valve-case, a tubular arm between the stand-pipe and valve-case, and a lever pivoted upon 45 the tubular arm and actuated by the pull, substantially as set forth.

4. In a water-closet valve, a case having three branches, one for the inlet-water, another for the pipe leading to the closet-basin, and a 50 third for leakage from the hole through which the valve-stem passes, substantially as set forth.

Signed by me this 19th day of March, A. D. 1883.

JOHN DEMAREST.
